Primary Examiner—Philip S. Hyder

(74) Attorney, Agent, or Firm—Joseph J. Previto

(57) **CLAIM**

The ornamental design of a foldable knife handle, as shown and described.

DESCRIPTION

FIG. 1 is a perspective view of my new design.

FIG. 2 is a top view thereof.

FIG. 3 is a side view thereof.

FIG. 4 is a front view thereof.

FIG. 5 is a rear view thereof.

FIG. 6 is a bottom view thereof.

FIG. 7 is another side view thereof.

FIG. 8 is a side view of the foldable knife handle with the broken line showing the blade holder apparatus in a partially folded position; and,

FIG. 9 is a side view of the foldable knife handle with the broken line showing the blade holder apparatus in a fully foldable position.

The broken lines showing the blade holder apparatus is for illustrative purposes only and forms no part of the claimed design.
